Sam A. Rosenthal

UNITED STATES PATENT OFFICE.

WOLFGANG E. SCHWARZMANN, OF LONGMEADOW, MASSACHUSETTS, ASSIGNOR TO
AMERICAN BOSCH MAGNETO CORPORATION, OF SPRINGFIELD, MASSACHUSETTS,
A CORPORATION OF NEW YORK.

JUMP-SPARK COLLECTOR.

Application filed January 11, 1921. Serial No. 436,624.

To all whom it may concern:

Be it known that I, WOLFGANG E. SCHWARZMANN, a citizen of the United States, residing at 51 Belleclaire Avenue, 5 Longmeadow, in the county of Hampden, State of Massachusetts, have invented certain new and useful Improvements in Jump-Spark Collectors; and I do hereby declare the following to be a full, clear, and exact 10 description of the invention, such as will enable others skilled in the art to which it appertains to make and use the same.

The present invention relates to collectors for magnetos, such as are used in ignition 15 systems for internal combustion motors.

In magneto collectors it was usual heretofore to provide the collector with a smooth conducting surface in the form of a ring or one or more segments of a ring, and a collecting brush in sliding contact therewith. 20 This construction requires the use of carbon, or the like as the material of the brush, which not only wears down but also tracks the ring with carbon which reduces the 25 electric resistance between the segments.

In accordance with one part of the invention, the collector has one or more conducting surfaces in the form of a ring or segments thereof, and a collecting electrode 30 suitably mounted in the casing of the magneto with the inner terminal of the electrode separated from the conducting surfaces to form a jump spark gap between them, thus eliminating the wear and tracking. If desired, the surface may be serrated, preferably 35 in the form of a knurled surface, so as to form a series of sparking points to aid the jumping of the spark.

A still further part of the invention, 40 whether or not the conducting surface on the collector be serrated or knurled, is to make the electrode hollow so as to permit air circulation and to aid in cooling the electrode from the heat generated by the sparks, and 45 also to provide the electrode with an annular groove for anchoring or maintaining it in fixed position in its mounting in the casing of the magneto.

In the accompanying drawing illustrating 50 preferred and modified embodiments of the invention:

Fig. 1 is a sectional view of the collector and an end of a magneto, constructed in accordance with my invention; Fig. 2 is a

top plan view with parts shown in section; 55 Fig. 3 is a transverse sectional view taken on line 3—3 of Fig. 2; and Fig. 4 is a similar view of Fig. 3 of a collector having a plurality of segments for use with a duplex or two-spark type of ignition system. 60

Referring more particularly to the drawing the magneto has a casing 1 in which is rotatably located a rotor 2 having a shaft 3 supported in ball bearings 4 in an end portion 5 of the casing. The shaft 3 carries, between the rotor and the bearings, a collector spool 6 having a metallic ring 7 in electrical connection with the secondary coil of the rotor in the usual manner. 65

Upon the end of the casing above the 70 spool 6, is mounted an electrode or brush cap 8 of hard rubber or similar material, secured in position by a screw 9 threaded into the casing portion 5, as is clearly shown in Figs. 1 and 2. The cap 8 has molded there- 75 in a hollow insert member or electrode 10, preferably of brass, the inner or upper end of which is bored and threaded to receive a screw 11, having a suitably tapered or sharp- 80 ened point 12 for piercing into and through the end of the lead 13. The body portion of the electrode may be provided with an annular recess 14 for receiving an integral molded projection of the cap which prevents the loosening of the insert in the cap. By mak- 85 ing the electrode hollow, its radiating surface is increased.

The conducting surface of the ring 7 is serrated or knurled so as to provide a plurality of projections or sparking points 15 90 thereon. The terminal or end 16 of the insert 10 is separated from the serrated or knurled surface 15 of the collector so as to provide therebetween a spark gap across 95 which a jump-spark may pass from the points 15 to the terminal 16.

The collector, however, may be made with two or more segments 7' with serrated or knurled surfaces so as to present a plurality of projections or sparking points 15', with 100 which may co-operate two or more collecting electrodes 10' molded in place in the caps 8, and having the screw pins 11', for piercing the leads 13', as in the structure shown in Figs. 1, 2 and 3. By providing sparking points on the rotating collecting ring or segments, the spark may jump from the former to the electrode with facility. The gap adds 105

- to the efficiency and strength of the spark at the spark plugs in the cylinders of the engine. By providing the collector with two segments and collecting electrodes the sparks 5 may be furnished with a duplex or two-spark system of ignition in which the two spark plugs of each cylinder are simultaneously operated to ignite the explosive charges therein at at least two points.
- 10 Having thus described my invention what I claim is:
1. In a magneto, in combination, a wound armature, a casing, a collector carried by said armature to rotate therewith and having a serrated conducting surface, and an electrode mounted in the casing with its inner terminal separated from the serrated surface for forming a jump spark gap therewith.
  - 15 2. In a magneto, in combination, a wound armature, a casing, a collector carried by said armature to rotate therewith and having a conducting surface which is roughened to form a plurality of sparking points, and an electrode mounted in the casing with
  - 20 its inner terminal separated from the roughened surface for forming a jump spark gap therewith.
  - 25 3. In a magneto, in combination, a wound armature, a casing a collector carried by said armature to rotate therewith and having a conducting surface, and a hollow collecting electrode mounted in said casing with its inner terminal separated from said surface for forming a jump spark gap there- 35 with.
  4. In a magneto, in combination, a wound armature, a casing, a collector carried by said armature to rotate therewith and having a conducting surface, and a hollow collecting electrode mounted in the casing with its inner terminal separated from said surface for forming a jump spark gap there- 40 with, said electrode having an annular groove for maintaining said electrode in 45 fixed relation in its mounting.

In testimony whereof I affix my signature.

WOLFGANG E. SCHWARZMANN.
